UNITED STATES PATENT OFFICE.

HARRY PRICE STURM, OF CLARKSBURG, WEST VIRGINIA.

MULTIPLE-INTAKE MANIFOLD.

1,347,598.

Specification of Letters Patent.

Patented July 27, 1920.

Application filed April 11, 1919. Serial No. 289,229.

To all whom it may concern:

Be it known that I, HARRY PRICE STURM, a citizen of the United States, and a resident of Clarksburg, in the county of Harrison 5 and State of West Virginia, have invented certain new and useful Improvements in Multiple-Intake Manifolds, of which the following is a specification.

My invention relates to improvements in 10 internal combustion engines, it being more particularly an improvement in the manifold for conducting the motive fluid to the engine, and it consists in the constructions, combinations and arrangements herein described and claimed.

The foremost object of the invention is to 20 provide a manifold for an internal combustion engine, which is so designed and constructed that the proper velocity of the fuel is maintained at all engine speeds, retaining the original atomization created in the carbureter, and preventing condensation on the walls of the manifold.

A further object of the invention is to 25 provide a multiple conduit manifold, wherein in certain of the conduits are employed at low engine speeds, and others are automatically cut in when the engine speeds up, accordingly increasing the area of the passage 30 for the flow of fuel and thus accommodating the increased volume necessary at high speeds.

A further object is to provide in a multiple conduit intake manifold as above described, means whereby the auxiliary or high speed conduit can be cut in either automatically or manually.

A further object of the invention is to 40 provide a novel type of manifold for internal combustion engines, by the use of which a great percentage of fuel is saved by preventing condensation thereof on the walls of the manifold.

Other objects and advantages will appear 45 in the following specification, reference being had to the accompanying drawings, in which:—

Figure 1 is a perspective view illustrating 50 the application of the invention to an internal combustion engine,

Fig. 2 is a vertical longitudinal section of the improved manifold, parts being shown in elevation,

Fig. 3 is an enlarged sectional view, 55 showing the vacuum operated valve in the

distributer block and its operating mechanism, more clearly,

Fig. 4 is a detail plan view showing the distributer block applied to the carbureter, and the mechanism for operating the various valves on the inside, 60

Fig. 5 is a detail sectional view taken substantially on the line 5—5 of Fig. 2 and showing how the low speed passage or conduit is applied to the distributer block, and 65

Fig. 6 is a section taken substantially on the line 6—6 of Fig. 3.

It should be stated in developing and perfecting my improved multiple manifold, due 70 recognition has been taken of what has been done in the prior art, and especially as represented in the patent to Piatt M. Orlopp, patented November 9, 1915, #1,159,985. This patent shows the employment of a plurality of conduits but in addition to these, 75 my improved manifold has other peculiar and important features as will presently be more fully explained.

The multiple intake manifold consists of 80 two or more pairs of passages or conduits 1, 2. The conduits 1 are smaller in diameter than the conduits 2.

Each set of conduits is of substantially 85 the same shape, that is to say, both branch out from the distributer block 3 which is suitably secured to the carbureter 4, and so conduct the fuel from the carbureter to the conduits of the manifold. The difference 90 between the two sets of conduits may here be noted. The small or low speed conduits first enter the distributer block 3 before they merge into the single passage 5, shown in Fig. 5.

On the other hand, the auxiliary or high speed conduits 2 are combined at 6 in Fig. 95 1, where they merge into a single conduit 7, which in turn is applied in any suitable way to the block 3. The upper ends of the respective pairs of conduits are fixed in conduit receivers 8. These consist of suitably shaped bodies that are arranged to be fitted into the valve supporting structures 9 on the engine 10.

It is to be understood that the multiple manifold can be applied to the engine in any 100 desirable manner and to this end, the use of the particular arrangement of conduit receivers 8 may be done away with altogether and some other arrangement substituted. Regardless of what the particular construc- 110

- tion of the manifold is, the primary purpose of the provision of a plurality of conduits of different diameters is to prevent the condensation of the fuel on the walls of the manifold at low engine speed, and to provide a manifold of sufficient area to accommodate the increased volume of fuel at high engine speeds, always maintaining a sufficient velocity.
- 10 In furtherance of the principles of the invention, the distributor block 3 is provided with a vacuum operated valve 11 which opens automatically when the engine speeds up. Under ordinary conditions, the valve 11 does not open, but the engine is supplied with fuel from the carburetor 4 through the low speed conduit 1, and the throttle valve 12 controls the flow of fuel under all circumstances.
- 15 The throttle valve 12 has an arm 13 to which the link 14 is connected. In the present instance, the other end of the link 14 is joined to a bell crank 15 which has a rod connection 16 that leads within reach of the operator. As the rod 16 is moved back and forth, the throttle valve 12 is opened and closed accordingly.
- 20 In order not to affect the valve 11 under ordinary circumstances by moving the rod 16 back and forth, but at the same time, making provision for manually opening the valve 11 irrespective of the increased suction in the engine, provision is made for opening the valve 11 from the link 14 when the link has moved a predetermined distance. It is plainly shown in Fig. 1 that the bifurcated end 17 of an arm 18, partly embraces the link 14 so that it may be engaged by the adjustable stop 19 on the link.
- 25 The arm 18 is affixed to the exposed end of the cam rod 20 which is suitably journaled in the block 3 and carries a cam 21 which operates against the end of the valve stem 22 of the valve 11. A spring 23, suitably disposed in the valve cage 24, normally keeps the valve 11 seated. The cage 24 is screwed in place in the internally threaded bore 25, by means of a spanner wrench or other suitable implement that is applied to
- 30 the notches in the outer end of the valve cage. The bore 25 merges with an annular enlargement 26 in the block 3, which is for the purpose of enabling the opening of the valve 11 and maintaining a uniform and undiminished fuel passage to the auxiliary manifold 2.
- 35 Fig. 6 shows how the cam shaft 20 is journaled in the distributor block 3. Portions of the block are removed at 27 and consequently suitably shaped to receive the shaft. Fillers 28 are then applied to hold the shaft in place. This is only one way of supporting the shaft and if in actual practice some other way may be found better, obviously the better way would be employed. The

advantage of the present arrangement is, that the shaft 20 can be taken out by simply removing the fillers 28.

The operation.

Under ordinary circumstances, the suction of the engine is not great enough to unseat the valve 11 and consequently at low engine speed, the fuel passes to the various cylinders of the engine through the low speed conduits 1 which are relatively small in diameter.

It is intended primarily that the valve 11 shall act automatically altogether and, at the same time, the advantage of opening the valve by manual means is also desired to be retained. Both purposes can be carried out by varying the adjustments or locations of the abutment 19. When the abutment is adjusted near the arm 18, the valve 11 will be caused to open a little before the suction of the engine becomes great enough to unseat the valve of its own accord. In other words, the throttle valve 12 is capable of manual adjustment under ordinary circumstances, and when opened to a predetermined place, as when it is desired to speed up the engine, the valve 11 is also unseated to accommodate the increased flow of fuel and consequently fuel is conducted to the engine through all of the conduits of the manifold.

In conclusion it is desired to say that instead of making the conduits 1 and 2 as separate members, they may be cored passages in a single manifold casting.

While the construction and arrangement of the multiple intake manifold as herein described and claimed, is that of a generally preferred form, obviously modifications and changes may be made without departing from the spirit of the invention or the scope of the claims.

I claim:—

1. A distributor block for a multiple manifold, having passages for receiving low speed sets of conduits and auxiliary sets of conduits, the auxiliary conduit passage including an annular enlargement merging into a valve cage bore, a valve cage fitted in said bore, a spring-seated valve in said cage arranged to open into the annular enlargement by virtue of increased engine speed, a cam shaft journaled on said block, a cam on said shaft operating against the stem of the valve, and an externally applied arm on said shaft, arranged to be operated by associated throttle valve actuating means.

2. The combination, of a carburetor throttle valve, a multiple intake manifold including a normally open set of conduits, a normally closed set of conduits, means operatively associated with the second set of conduits keeping them normally closed but being capable of opening on an increase of

engine speed above a predetermined limit, and manually operated means for actuating the throttle valve, embodying devices constituting alternative means for actuating 5 said conduit closing means irrespective of increased engine speed.

3. The combination, of a carbureter throttle valve, a multiple intake manifold including a normally open set of relatively 10 small conduits, a normally closed set of conduits of larger diameter, means operatively associated with the second set keeping them normally closed but being capable of opening on an increase of engine speed above a 15 predetermined limit, and manually operated means for actuating the throttle valve, embodying devices constituting alternative means for actuating said conduit closing means irrespective of increased engine speed.
4. The combination, of a carbureter with an applied distributor block, a multiple manifold consisting of separate sets of conduits branching out from said block, one set of said conduits being in constant communication with the carbureter, but the other set being normally closed; a throttle valve in the carbureter, with connected devices for manually operating it; an engine speed-responsive member normally closing 25 said second set of conduits to the carbureter, but capable of opening on an increase of en-

gine speed above a predetermined limit, thus connecting all of the conduits with the carbureter; and adjustable connected members 35 co-operatively associated between said speed-responsive members and the operating devices of the throttle valve, enabling manual operation of said speed-responsive members.

5. A multiple intake manifold, comprising a set of conduits merging into a single 40 passage in a distributor block at one end, and entering separate conduit receivers at the other ends; an auxiliary set of conduits, of larger diameter merging into a single passage before entering the distributor block, 45 and connected to said receivers at the other end; a valve cage with a normally seated valve in operative association with said auxiliary set of conduits and keeping said set normally closed through said distributor 50 block, associated carbureter throttle valve operating means including a reciprocating link with an adjustable abutment, and means for manually unseating the valve in said cage, including a cam shaft with an arm 55 arranged to be engaged by said abutment, and a cam arranged to operate against the steam of said valve.
